(57) **CLAIM**

The ornamental design for a collapsible container, as shown and described.

DESCRIPTION

FIG. 1 is an exploded isometric front perspective view of a collapsible container in an uncollapsed configuration in accordance with the present design;

FIG. 2 is an exploded isometric front elevational view thereof;

FIG. 3 is an exploded isometric rear elevational view thereof;

FIG. 4 is an exploded isometric right side elevational view thereof;

FIG. 5 is an exploded isometric left side elevational view thereof;

FIG. 6 is a top plan view of the exploded isometric view of FIGS. 1-5;

FIG. 7 is a bottom plan view of the exploded isometric view of FIGS. 1-5;

FIG. 8 is a front perspective view of the collapsible container in a collapsed configuration in accordance with the present design;

FIG. 9 is an exploded isometric front perspective view of an alternative embodiment in accordance with the present design of FIG. 1;

FIG. 10 is an exploded isometric front elevational view of the alternative embodiment illustrated in FIG. 9;

FIG. 11 is an exploded isometric rear elevational view thereof of the alternative embodiment illustrated in FIG. 9;

FIG. 12 is an exploded isometric right side elevational view thereof of the alternative embodiment illustrated in FIG. 9;

FIG. 13 is an exploded isometric left side elevational view thereof of the alternative embodiment illustrated in FIG. 9;

FIG. 14 is a top plan view of the exploded isometric view of the alternative embodiment illustrated in FIGS. 9-13;

FIG. 15 is a bottom plan view of the exploded isometric view of the alternative embodiment illustrated in FIGS. 9-13; and,

FIG. 16 is a front perspective view of the collapsible container of the alternative embodiment illustrated in FIG. 9 in a collapsed configuration.

The broken lines shown in the drawings illustrate portions of the collapsible container that form no part of the claimed design.

The stippling in the drawings is for shading purposes only.
